UNITED STATES PATENT OFFICE.

WILLIAM H. PERRY, OF CONCORD, NEW HAMPSHIRE.

DESIGN FOR A MONUMENT.

SPECIFICATION forming part of Design No. 21,475, dated April 19, 1892.

Application filed March 14, 1892. Serial No. 424,898. Term of patent 3½ years.

To all whom it may concern:

Be it known that I, WILLIAM H. PERRY, a citizen of the United States, residing at Concord, in the county of Merrimac and State of New Hampshire, have invented and produced a certain new and original Design for Monuments, of which the following is a specification.

In the accompanying drawing, figures and letters of reference will be used to designate the distinguishing features of my design.

The base is shown at 1 and is oblong in form, having four vertical sides terminating at their tops in an obtuse frustum of a pyramid, (shown at 2,) upon which rests the pedestal 3, which is also oblong and has four vertical sides terminating in an acute frustum of a pyramid, (shown at 4,) one or more sides of which are provided with a raised tablet 5. An oblong shaft 6, having four vertical sides, terminates at the top in the form of an obtuse wedge 7. The lower end of said shaft 6 terminates in an inverted frustum of a pyramid 8, which meets the upper end of the frustum 4.

Another feature of my design is the ornamentation of the shaft 6, consisting of a depressed tablet 9, to be formed upon one or more of its vertical sides, and the V-grooves 10, located one near the top and one near the bottom edge of each of the said vertical sides. The ornamentation further consists in surfaces of a different character, as seen at A, B, and C, those shown at A representing rock-work, at B hammered work, and at C polished work. The tablet 9 is finished in both hammered and polished work, each having the configuration shown.

Having described my improved design, what I claim is—

The design for a monument, substantially as herein described and shown.

In testimony whereof I affix my signature in presence of two witnesses.

WILLIAM H. PERRY.
